Attorney S

UNITED STATES PATENT OFFICE

CHARLES BOFFINO, OF LOS ANGELES, CALIFORNIA

PACKAGE SEAL

Application filed January 25, 1932. Serial No. 588,706.

This invention relates to certain new and useful improvements in package seals.

The primary object of the invention is to provide a package seal wherein the ends of the tying cord are confined within the seal member to prevent access thereto for unauthorized opening of a package or the like.

A further object of the invention is to provide a package seal comprising a pair of plate or disk members between which a tying cord is positioned with the end of the tying cord severed at a point within the peripheral edges of the plates or disks so that access thereto is impossible for untying a package or the like.

With the above and other objects in view that will become apparent as the nature of the invention is better understood, the same consists in the novel form, combination and arrangement of parts hereinafter more fully described, shown in the accompanying drawing and claimed.

In the drawing:—

Figure 1 is a perspective view of the seal associated with the package;

Figure 2 is a fragmentary side elevational view of the seal associated with a bottle neck;

Figure 3 is a top plan view of the package seal;

Figure 4 is a vertical longitudinal sectional view of the seal showing the upper double wall construction of the same;

Figure 5 is a sectional view, similar to Figure 4 showing the tying cord disposed between the upper walls of the seal;

Figure 6 is a vertical longitudinal sectional view of another form of seal with a pin connecting the upper and lower walls of the seal; and

Figure 7 is a sectional view, similar to Figure 6 showing the upper walls of the seal separated.

Referring more in detail to the accompanying drawing and particularly to Figures 1 to 5, there is illustrated a seal formed of a pair of opposed dished circular plates or walls 10 and 11, constituting respectively, upper and lower walls of the device, the upper wall 10 having a peripheral angularly directed flange 12 for confining the peripheral

edge of the bottom wall 11. A pin 13 extends centrally through the upper wall 10 and is headed upon opposite ends thereof, the upper headed end confining a dished disk 14 mating with the upper dished wall 10, the disk 14 being of slightly less diameter than the upper wall 10 and being provided upon its edge with a rolled bead 15 as illustrated. The disk 14 is normally retained, substantially engaged with the wall 10 by the resilient or cushioning member 16 mounted upon the pin 13 at the inner side of the upper wall 10 and is retained upon said pin by the lower head thereof, aided by the key 17. As shown in Figures 3 to 5, a pair of mating annular beads 18 are formed in the upper wall 10 and disk 14 adjacent the peripheral edges thereof and said disk 15, inwardly of and adjacent its bead 18 is provided with a relatively short radial slit 19.

In applying the seal to a package, such as illustrated at 20 in Figure 1, one end of a cord 21 is introduced between the wall 10 and disk 14 to be wound several times around the pin 13, the thickness of the cord separating the disk 14 from the wall 10 against the pressure of the resilient or cushioning member 16 with the disk then occupying the position relative to the wall 10 shown in Figure 5. The cord is then wrapped around the package 20 and associated with the seal with the terminal end thereof wound several times around the pin 13 between the disk and wall with the convolutions of the cord lying within the mating beads 18. A knife blade or similar device is then inserted through the slit 19 in the disk 14 for severing the free ends of the tying cord 21 between the disk 14 and wall 10 at a point within the beads 18 so that access to the free end of the cord is prevented. In a similar manner, the seal may be associated with the bottle 22 illustrated in Figure 2 so that the cork or cap of the bottle cannot be removed without detection.

In the form of invention illustrated in Figures 6 and 7, the resilient or cushioning member 16 has been eliminated while the pin 13a is connected to the central portions of the upper wall 14a and the flat bottom wall 11a,

the peripheral edge of the bottom wall 11a being confined within the flange 12a at the edge of the upper wall 10. The upper plate or disk 14a is rotatable upon the upper end 5 of the pin 13a, the wall 10a being movable downwardly over the pin 13a as illustrated in Figure 7 to facilitate positioning of the tying cord between the wall 10a and disk 14a, the seal in other respects operating in a manner similar to the form of invention illustrated in Figure 5.

While there are herein shown and described the preferred embodiments of the invention, it is nevertheless to be understood that minor 15 changes may be made therein without departing from the spirit and scope of the invention as claimed.

I claim:—

20 In a package seal, a dished wall and a dished disk supported above the wall, mating annular beads adjacent the edges of the wall and disk and said disk having a radial slit therein inwardly of and adjacent the beads, a dished bottom wall in opposed relation to 25 the aforesaid wall and a flange on the first named wall for retaining the bottom wall in assembled relation thereto.

In testimony whereof I affix my signature.

CHARLES BOFFINO.
